UNITED STATES PATENT OFFICE.

GEORGE FRANKLIN LEBUS, OF ELECTRA, TEXAS.

ELEVATOR-WRENCH.

1,113,659.

Specification of Letters Patent.

Patented Oct. 13, 1914.

Application filed January 27, 1914. Serial No. 814,660.

To all whom it may concern:

Be it known that I, GEORGE F. LEBUS, a citizen of the United States, and a resident of Electra, in the county of Wichita and 5 State of Texas, have invented a new and useful Improvement in Elevator-Wrenches, of which the following is a specification.

My invention is an improvement in elevator wrenches, and has for its object to provide a device of the character specified, for 10 use in rotary drilling machines for supporting the drill pipe and for holding it from rotation during the releasing of the several joints of the pipe when it is necessary to 15 withdraw the drill from the well hole.

In the drawings:—Figure 1 is a top plan view of the improved wrench, Fig. 2 is a section on the line 2—2 of Fig. 1, looking in the direction of the arrows, Fig. 3 is a side 20 view of the wrench, and Fig. 4 is a section on the line 4—4 of Fig. 3, looking in the direction of the arrows.

The present embodiment of the invention is shown in connection with a flanged nipple, 25 the said nipple comprising a plate 1 of approximately rectangular shape and having a central opening through which extends one end of a sleeve 2, and the ends of the sleeve are flanged as shown at 3, the upper face of 30 the plate 1 being counterbored as shown to receive the upper flange of the sleeve.

A plurality of right-angled brace brackets 4 is arranged between each end of the plate 1 and the sleeve, and between each pair of 35 brackets a reinforcing bar 5 is arranged on the under face of the plate. Pins 6 are passed through registering openings in the bars and the ends of the plate, and the said pins are secured in place in any desired manner. 40 The flanged nipple is placed over the pipe as indicated in Fig. 2, the pipe being indicated in dotted lines and the improved wrench engages the pipe above the nipple.

In rotary well drilling the drill machine is 45 provided with four gripping rings, which are tightened on the drill pipe, so that the sharp edges of the grip rings bear against the pipe, after which the machine is started and the drill pipe is turned until the drill 50 becomes dull. The drill pipe must then be raised out of the well hole, and the dulled drill replaced by a sharp one. With the flanged nipple, when the bit becomes dulled, the rotary machine is released to permit the 55 flanged nipple to drop in between the grip

rings and the pipe. The machine is then tightened on the nipple, and the drill pipe is raised out of the well hole.

The wrench is in the form of a split sleeve or collar 7, the opening 8 or split of the collar being of the same width as the diameter of the bore of the collar, so that the collar can be placed on the pipe 9 laterally. At each end the collar is externally reinforced by a rib 10, the said ribs extending radially 60 and from one side of the split or opening to the other.

The split ends of the collar are enlarged to form spaced bearing lugs or ears 11 and 70 12 respectively, at each side of the split or opening 8, and a gripping jaw 13 is pivoted between the ears 11, by means of a pivot pin 14 or the like. A lever 15 is pivoted between the ears or lugs 12, by means of a pivot pin 16, and the said lever is provided with a reduced handle 17.

The pivot pin 16 passes through the ears or lugs 12 of the collar and through an extension lug 18 of the lever, the said lug extending in the opposite direction to the handle. The extremity of the jaw 13 is reduced at the end remote from the pivot pin 14 as indicated at 20, and the said reduced portion is adapted to enter a recess 21 in the inner end of the lever 15 and in the inner adjacent 80 edge of the lug 18. The inner end of the lever and the inner edge of the extension lug 18 are serrated as shown at 19, above and below the recess. The inner edge of the jaw 13 is also serrated as shown at 22, and it will 90 be noted that the serrations or teeth 19 and 22 are shaped like ratchet teeth and face in the same direction.

The lever 15 is provided with a transverse vertical opening 23, and the upper end of 95 the opening is counterbored as shown at 24. A bolt 25 is passed through the opening 23—24, and the lower end of the bolt is engaged by a nut 26 to prevent disengagement of the bolt. A coil spring 29 encircles the bolt in the counterbored portion 24 of the opening, the spring bearing at one end against the head of the bolt and at the other end against the annular shoulder formed between the counterbored portion of the 100 opening and the main portion thereof. The collar is also provided at its lower end with an extension 30, the said extension being of greater thickness than the thickness of the collar and having its outer surface flush with 105 110

the outer surface of the collar between the ribs 10. The internal diameter of the extension is thus less than that of the collar, and a shoulder 31 is formed between the 5 extension and the collar. The extension is adapted to fit within the portion 2 of the nipple as shown in Fig. 2, and the under face of the lowermost reinforcing rib 10 is adapted to engage the upper face of the 10 plate 1 to limit the downward movement of the wrench.

The collar 7 is of a size internally to receive the union which connects the joints of pipe, while the extension 30 is of an internal 15 diameter to receive the pipe proper. The collar is also provided with oppositely arranged rings 32, for engagement by lifting means to lift the wrench and the pipe.

When it is desired to arrange the wrench 20 on the pipe, the flanged nipple is first placed as shown in Fig. 2. The gripping jaw is then swung into the dotted line position of Fig. 1, and the lever 15 is swung away from the gripping jaw 13 to permit the pipe 25 to enter the collar by way of the split or opening 8. The extension 30 of the collar engages within the tubular portion of the nipple and the said extension is of such thickness that it will just fill the space between the pipe and the inner surface of the 30 nipple as shown in Fig. 2. After the collar has been placed as above mentioned, the gripping jaw 13 is swung into the full line position of Fig. 1 with the reduced portion 35 or lug 20 received in the recess 21 of the lever. When now the handle of the lever is swung toward the observer in Fig. 1, the teeth of the gripping jaw 13 will be forced into engagement with the peripheral surface 40 of the pipe, tightly clamping the same between the inner surface of the collar and the gripping jaw 13. The union 33 connecting the joints of the pipe is adapted to fit within the collar, the pipe proper being 45 received within the extension 30, and the internal diameter of the collar is of a size to receive the said union. The lower end of the union rests upon the shoulder or ledge 31, and the under face of the lowermost reinforcing rib 10 rests upon the upper face 50 of the plate 1, thus preventing downward movement of the pipe. The lifting mechanism is connected with the rings 32 and it will be evident that the pipe will be firmly held from downward movement.

The operation is as follows:—When the bit becomes dull and it is necessary to replace it, the pipe must be withdrawn from the well hole. It will be understood that the 60 drill pipes are of great length, as for instance, 2,000 feet, and the said pipe consists of sections connected by unions or coupling sleeves 33. The pipe is lifted, and as it is lifted the several joints are released by unscrewing them from the union, the upper-

most section of pipe being screwed out of the union leaving the union connected with the next lower joint of pipe. As each union appears above the well hole, the entire pipe is raised until the union is a foot or so 70 above the top of the flanged nipple, that is, above the top of the plate 1. Then the improved wrench is placed on the pipe, and the extension 30 is permitted to slip down into the position shown in Fig. 2. The pipe is 75 then lowered until the lower end of the union 33 rests upon the shoulder 31. The jaw 13 is arranged as shown in Fig. 1, and a pipe wrench is connected with the joint of pipe above the union within the wrench. 80 As the pipe wrench is moved in a direction to unscrew the uppermost joint, the handle 17 of the lever will be brought into contact with one of the pins 6, and the more pressure that is brought to bear upon the pipe wrench, the more tightly will the handle be pressed against the pin 6, and the more tightly the teeth 19 and 22 will be pressed against the peripheral surface of the union. The union 33 within the wrench is absolutely 85 prevented from movement with the pipe wrench so that the uppermost joint may be easily detached. After the said joint has been detached, the elevating mechanism is engaged with the links 32 and the entire 90 pipe is lifted until the next union is above the well hole after which the operation is repeated.

It will be understood that the drilling machine is reversed to release the pipe sections 100 in succession. It will be noticed that the outer end of the reduced portion 20 of the gripping jaw is rounded or cam shaped, for engagement by the cam shaped bottom wall of the recess 21. When the lever is swung 105 toward the observer in Figs. 1 and 4, the lug 34 which extends at approximately a right angle to the handle bears against a rounded cam of the portion 20 to force the gripping jaw toward the pipe.

The bolt 25 constitutes a lock, and it will be noted that the counterbored portion of the opening is of sufficient size to receive the head of the bolt so that the bolt can be depressed against the resistance of the spring. 115 The head of the bolt and the nut normally extend above and below the lever, and the uppermost ear of the pair 12 is provided with an extension 35 for engagement by the head when it is in the position shown in 120 Fig. 2 to prevent the lever 15 from swinging far enough to release the lug 20 of the gripping jaw from the recess 21 of the lever. The said lug cannot be released from the lever until the bolt is depressed a sufficient 125 distance to cause the head to enter the counter-bored portion of the opening, and the wrench cannot be released from the pipe until the gripping jaw 13 is released from the lever. Thus a lock is provided for pre- 130

venting the entire detachment of the wrench from the pipe while permitting the parts to take a position such that the wrench will move freely vertically on the pipe.

5 I claim:

1. A device of the character specified, comprising a flanged nipple consisting of a tubular portion of greater diameter than the pipe and through which the pipe is adapted 10 to pass, and a plate at the upper end of the tubular portion, said plate having a stop at each end thereof and on the upper face of the plate, a wrench comprising a split collar of a diameter to receive the union, the split 15 of the collar being of the same diameter as the collar, said collar having a depending extension adapted to fit between the inner surface of the tubular portion of the nipple and the pipe, the wrench having a shoulder 20 between the extension and the collar for engagement by the lower end of the union, said collar having at each end vertically spaced bearing lugs, a gripping jaw pivoted between one pair of lugs and adapted to swing 25 toward the other pair and having its inner edge serrated for engaging the union, a lever pivoted between the other pair of lugs and having its inner end serrated and provided with a recess, the gripping jaw having 30 a reduced extension fitting within the recess, said lever being adapted to engage one of the stops of the plate when the pipe is turned to force the gripping jaw into engagement with the union, said collar having 35 oppositely arranged rings for engagement by lifting mechanism.

2. A device of the character specified, comprising a flanged nipple consisting of a plate having a central opening for permitting 40 the passage of the drill pipe and a tubular portion extending downwardly from the opening for encircling the pipe, said nipple having stops on the upper face and at the ends of the plate, and a wrench comprising 45 a split collar for engaging the pipe laterally and of a diameter to receive a union, the collar having a depending extension of a diameter to fit the pipe, the extension being split to permit it to engage the pipe laterally, the wrench having an annular shoulder between the collar and the extension for engagement by the lower end of the union, and having an annular shoulder between the collar and the extension for engaging the upper face of the plate, a gripping jaw pivoted to one end of the split collar and having serrations for engaging the union, a lever pivoted to the other end, said lever having a recess in its inner end, and the gripping jaw having a reduced lug fitting within the recess, the lever being adapted to engage a stop of the plate to force the gripping jaw toward the pipe.
3. A device of the character specified, comprising a flanged nipple consisting of a plate having a central opening for permitting 50 the passage of the drill pipe and a tubular portion extending downwardly from the opening for encircling the pipe, said nipple having stops on the upper face and at the ends of the plate, and a wrench comprising 55 a split collar for engaging the pipe laterally and of a diameter to receive a union, the collar having a depending extension of a diameter to fit the pipe, the extension being split to permit it to engage the pipe laterally, the wrench having an annular shoulder between the collar and the extension for engagement by the lower end of the union, and having an annular shoulder between the collar and the extension for engaging the upper face of the plate, a gripping jaw pivoted to one end of the split collar and having serrations for engaging the union, a lever pivoted to the other end, said lever having a recess in its inner end, and the gripping jaw having a reduced lug fitting within the recess, the lever being adapted to engage a stop of the plate to force the gripping jaw toward the pipe.
4. A device of the character specified, comprising a sleeve through which a drill pipe and its union are adapted to pass, a plate at the upper end of the sleeve and secured thereto, said plate having at each end an upwardly extending stop, a wrench comprising a split collar for engaging a union of the drill pipe laterally and having a depending extension adapted to fit the pipe, the wrench having internal and external shoulders at the junction of the extension therewith for engaging the lower end of the union and the upper face of the plate respectively, clamping means in connection with the collar for gripping the union, a lever pivoted to the collar and adapted to engage the clamping mechanism and to cause the same to grip the union when the lever is swung in one direction, the lever being adapted to engage one of the stops of the plate to operate the clamping mechanism.
5. A device of the character specified, comprising a wrench consisting of a split collar of a diameter to slip over a union laterally and having a depending extension of less diameter for receiving the pipe below the union, the wrench having a shoulder for engagement by the lower end of the union, a gripping jaw pivoted to one end of the collar, a lever pivoted to the other end and having an extension for engaging the gripping jaw to force it toward the union when the lever is swung in one direction.

to permit the outward swinging movement of the lever to prevent the entire release of the gripping jaw until the lock is released.

3. A device of the character specified, comprising a flanged nipple consisting of a plate having a central opening for permitting the passage of the drill pipe and a tubular portion extending downwardly from the opening for encircling the pipe, said nipple having stops on the upper face and at the ends of the plate, and a wrench comprising a split collar for engaging the pipe laterally and of a diameter to receive a union, the collar having a depending extension of a diameter to fit the pipe, the extension being split to permit it to engage the pipe laterally, the wrench having an annular shoulder between the collar and the extension for engagement by the lower end of the union, and having an annular shoulder between the collar and the extension for engaging the upper face of the plate, a gripping jaw pivoted to one end of the split collar and having serrations for engaging the union, a lever pivoted to the other end, said lever having a recess in its inner end, and the gripping jaw having a reduced lug fitting within the recess, the lever being adapted to engage a stop of the plate to force the gripping jaw toward the pipe.

4. A device of the character specified, comprising a sleeve through which a drill pipe and its union are adapted to pass, a plate at the upper end of the sleeve and secured thereto, said plate having at each end an upwardly extending stop, a wrench comprising a split collar for engaging a union of the drill pipe laterally and having a depending extension adapted to fit the pipe, the wrench having internal and external shoulders at the junction of the extension therewith for engaging the lower end of the union and the upper face of the plate respectively, clamping means in connection with the collar for gripping the union, a lever pivoted to the collar and adapted to engage the clamping mechanism and to cause the same to grip the union when the lever is swung in one direction, the lever being adapted to engage one of the stops of the plate to operate the clamping mechanism.

5. A device of the character specified, comprising a wrench consisting of a split collar of a diameter to slip over a union laterally and having a depending extension of less diameter for receiving the pipe below the union, the wrench having a shoulder for engagement by the lower end of the union, a gripping jaw pivoted to one end of the collar, a lever pivoted to the other end and having an extension for engaging the gripping jaw to force it toward the union when the lever is swung in one direction.

the gripping jaw having a reduced lug at its outer end and the lever a recess at its inner end for engagement by the lug, a releasable lock in connection with the lever for 5 limiting the outward swinging movement of the same to prevent the entire release of the gripping jaw, and a nipple through which the pipe is adapted to extend, the extension being received between the pipe and 10 the inner surface of the nipple, said nipple having stops for engagement by the outer end of the lever to cause the lever to operate the gripping jaw when the wrench is swung in one direction.

15 6. A device of the character specified, comprising a wrench consisting of a split collar of a diameter to slip over a union laterally and having a depending extension of less diameter for receiving the pipe below the union, the wrench having a shoulder for engagement by the lower end of the union, a gripping jaw pivoted to one end of the collar, a lever pivoted to the other end and having an extension for engaging 20 25 the gripping jaw to force it toward the union when the lever is swung in one direction, the gripping jaw having a reduced lug at its outer end and the lever a recess at its inner end for engagement by the lug, a releasable lock in connection with the lever for limiting the outward swinging movement of the same to prevent the entire release of the gripping jaw.

30 35 7. A device of the character specified, comprising a wrench consisting of a split collar of a diameter to slip over a union

laterally and having a depending extension of less diameter for receiving the pipe below the union, the wrench having a shoulder for engagement by the lower end of the union, a gripping jaw pivoted to one end of the collar, a lever pivoted to the other end and having an extension for engaging the gripping jaw to force it toward the union when the lever is swung in one direction, a nipple through which the pipe is adapted to pass, the extension being received between the pipe and the inner surface of the nipple, and the wrench having an external shoulder between the collar and the extension for engaging the upper end of the nipple, and the nipple having stops for engagement by the lever to swing it in a direction to move the gripping jaw toward the union when the wrench is swung in one direction.

8. A device of the character specified, comprising a wrench consisting of a split collar of a diameter to slip over a union laterally and having a depending extension of less diameter for receiving the pipe below the union, the wrench having a shoulder for engagement by the lower end of the union, a gripping jaw pivoted to one end of the collar, a lever pivoted to the other end and having an extension for engaging the gripping jaw to force it toward the union when the lever is swung in one direction.
